US00D364582S

United States Patent

[19]

Weder et al.

[11] Patent Number: Des. 364,582

[45] Date of Patent: **Nov. 28, 1995

[54] FLOWER POT COVER

[75] Inventors: **Donald E. Weder; Joseph G. Straeter**, both of Highland, Ill.

[73] Assignee: **Highland Supply Corporation**, Highland, Ill.

[*] Notice: The portion of the term of this patent subsequent to March 19, 2005 has been disclaimed.

[**] Term: **14 Years**

[21] Appl. No.: **807,897**

[22] Filed: **Dec. 16, 1991**

[57] CLAIM

The ornamental design for a flower pot cover, as shown and described.

DESCRIPTION

FIG. 1 is a perspective view of our new flower pot cover design;

FIG. 2 is a reduced side elevational view thereof;

FIG. 3 is a reduced top plan view thereof;

FIG. 4 is a reduced bottom plan view thereof;

FIG. 5 is a fragmentary enlarged top plan view thereof;

FIG. 6 is a fragmentary enlarged top plan view of the skirt edge design of a second embodiment of our new design;

FIG. 7 is a fragmentary enlarged top plan view of the skirt edge design of a third embodiment of our new design;

FIG. 8 is a fragmentary enlarged top plan view of the skirt edge design of a fourth embodiment of our new design;

FIG. 9 is a perspective view of a fifth embodiment of our new design;

FIG. 10 is a reduced side elevational view of the design of

FIG. 9 the only difference being the angle of the skirt;

FIG. 11 is a reduced side elevational view of the design of

FIG. 9, the only difference being the angle of the skirt;

FIG. 12 is a top plan view of a sixth embodiment of our new design;

FIG. 13 is a top plan view of FIG. 9; and,

FIG. 14 is a top plan view of a seventh embodiment of our new design.

The flower pot cover has no substantial thickness.

The characteristic feature of the design resides in the specific pleating arrangement comprised of the parallel disposition of the exterior folds in combination with the interior V-shaped folds, all as best shown in FIG. 1.
